UNITED STATES PATENT OFFICE

KARL E. PEILER, OF WEST HARTFORD, CONNECTICUT, ASSIGNOR TO HARTFORD-EMPIRE COMPANY, OF HARTFORD, CONNECTICUT, A CORPORATION OF DELAWARE

GLASS-ANNEALING LEER

Application filed January 9, 1930. Serial No. 419,506.

This invention relates to glass annealing leers and more especially to the construction of a glass annealing leer having a substantially helical flue for the passage of temperature controlling media about or adjacent to the tunnel through which the ware is passed for annealing.

I have shown my invention in connection with a leer of the type especially adapted for sheet glass; but it will be understood that some, if not all of the features herein described and claimed may also be of general utility in annealing all types of glassware.

The leer of my invention provides certain of the functional advantages present in the leer set forth in the patent to the Hartford-Empire Co., No. 1,560,481, granted November 3, 1925, assignee of Vergil Mulholland, and in certain aspects constitutes an improvement on that leer.

In constructing a leer having a flue either substantially or exactly in the form of a helix, it is inevitable either that the ware receiving end of the leer be so formed as to correspond to the angle of the helix, or if the leer is formed with a receiving end at right angles to the direction of movement of the ware, there will be a space at the receiving end, which is not included within the helical flue. In either case, undesirable effects are likely to be present due to the uneven heating of the glass, which in some instances carries a material distance down the leer and causes uneven thermal conditioning of the glass with the result that the glass is not properly annealed. An object of my invention is to overcome these difficulties by supplying heat to the space above mentioned which is located between the inclined portion of the foremost turn of the helical flue and the right angular end of the leer.

A further object of the invention is to insure the even heating of the leer by the prevention of the possibility of "hot spots" therein. This object is in general realized by locating of the fire box, which supplies the heated media to the leer, outside the vertical confines thereof, so that heat passing from the fire box to the glass in the interior of the tunnel must be transferred by the hot gases

rather than by direct conduction or radiation.

A further object of the invention is to design the flue-forming members of a substantially helical flue leer, so as to render them simple to construct and assemble, and more specifically, so that in the construction of these members, no cores are required for the castings, and the machining necessary is of the simplest kind. Also it is an object of the invention to design these flue-forming members in such a way that certain of the flue sections of each turn are at right angles to the direction of movement of the glass through the leer, while others are arranged diagonally thereof to connect opposite ends of contiguous right angular portions to form a continuous flue.

A further object is to construct these members in such a way that when assembled, contiguous flue passages are separated from each other by but one wall thickness and are separated from the interior of the tunnel also by but one wall thickness, which latter is a common wall between the flues and the tunnel, and which in itself forms the tunnel.

A further object of the invention is to provide a leer having a flattened helical flue associated therewith and defining the ware tunnel and having a conveying belt upon which the glass is carried which is of substantially the same width as the widest transverse dimension of the tunnel and in close proximity with a considerable portion of the flue.

Other objects and advantages of the invention will be apparent from a reading of the following specification and subjoined claims when taken in connection with the accompanying drawings, in which:

Figure 1 is a diagrammatic elevation of the entire leer;

Fig. 2 is a plan view of the leer as shown in Fig. 1 having parts broken away to show the interior construction;

Figs. 3 and 4 together constitute an elevation of the leer with certain parts broken away and in section to show the interior construction;

Fig. 5 is a transverse section substantially on the line 5—5 of Fig. 3;

Fig. 6 is a section substantially on the line 6-6 of Fig. 3;

Fig. 7 is a plan view of a portion of the entering end of the leer with certain parts broken away and in section to show the interior construction; and

Fig. 8 is a perspective of certain parts of the leer at the entrance end, the parts being separated for clarity of illustration and certain parts being broken away better to show their construction.

As diagrammatically illustrated in Figs. 1 and 2, the leer comprises a sectional tunnel A; a fire box B, preferably located at one side of the tunnel adjacent to its entrance end; a flue C communicating at one end with the fire box adjacent to the glass receiving end of the leer and extending uninterruptedly to the other end of the leer substantially in a helix, the end of the flue at the discharge end of the tunnel being open to the atmosphere; a draft producing device D, specifically a suction fan communicating with the flue C; a ware sorting and packing table E located at the exit end of the tunnel; and endless conveyor belt F, the ware-bearing strand of which traverses the tunnel and the table E and the idle strand of which returns to the entrance end of the tunnel beneath the leer; and a belt driving mechanism G.

The structural parts of the tunnel and temperature controlling flue are supported upon suitable framework including a pair of longitudinally extending members 1 rigidly maintained in position by a plurality of transversely extending structural members 2 (Fig. 6), this framework being supported at intervals by vertically adjustable pedestals 3. The tunnel may, if desired, be slightly inclined downwardly from its hot or receiving end to the cool or delivery end to cause a tendency for air to flow by natural convection through the tunnel in a direction opposite to that of the movement of the glass. This flow of air through the tunnel is preferably barely sufficient to prevent an inflow of harmful currents of cold air at the hot end of the tunnel, without itself exerting a material cooling influence upon the glass.

In order to control temperature in the tunnel, I prefer to conduct temperature controlling gases around it in a substantially helical path defined by a flue which is preferably made up of a plurality of substantially interchangeable members, which are of the minimum number of varieties, so as to facilitate the setting up of the leer and to minimize the expense of manufacture of the several parts. With the above objects in view, the tunnel is preferably made up of a plurality of flue-forming members 4 (Fig. 8), each constituting the bottom and sides of a single turn of the flue and provided with flanges 5 for attachment to the contiguous members 4. As shown in Fig. 8, members 4 comprise inner and

outer walls 6 and 7, and a single side wall 8 connecting them, the inner wall being substantially smooth and the outer wall 7 preferably being provided with ribs 4a to provide additional strength, so that when the sections 4 are assembled together, the inner walls 6 form the side and bottom walls of the tunnel. The first flue and tunnel forming section 4' is provided with a supporting flange portion 9, which may be suitably built into the brick work or other supporting structure at the entrance end of the leer, which end is anchored permanently against expansive movement. The members 4 are provided with trunnion supporting bosses 10 in which are mounted stub shafts 11 (Fig. 6) on which rollers or wheels 12 are journaled, the wheels running on the rails 1 to permit the leer to expand when heated. Members 4 and 4' are provided with upwardly facing flanges 13 to which are bolted or otherwise secured skew or diagonal flue members 14. The members 14 extend at an oblique angle to the direction of movement of the glass through the leer and each serves to connect one end of one of the members 4 with the opposite end of a contiguous member, suitable apertures 17 being provided in the bottom wall of the members 14 to connect with the passages of the members 4 as above described. The members 14 are preferably made up of angle members 15 and top covering members 16, which are provided with suitable flanges for attaching them by bolts or otherwise to members 4 and to each other. Members 14 are provided with end closures 17' preferably bolted thereto. Thus, it will be seen that the construction and assembly of the flue-forming members is extremely simple, as the parts may be easily cast or rolled, without requiring the use of intricate and expensive core members, and the necessary machining is of the simplest kind. Also the provision of members to form the flues having not more than three sides saves in the amount of material used as the walls between contiguous turns of the flue are single rather than double. This also aids in maintaining a smooth heat gradient as will be obvious.

Inasmuch as the top members 14 are inclined with respect to the direction of motion of the glass through the leer, and that the entering end 18 of the leer is formed at right angles to the direction of movement of the ware entering the leer, a substantially triangular space is left which, were it not for the special provision made herein, would be a dead space and entirely unheated, which would tend to render uneven the heating of the ware. In order to overcome the effect of this dead space, the member 4' is provided with a connecting passage by which a desired proportion of the hot gases from the fire box B may be conducted into the triangular member 19, which occupies the above de-

scribed space, a damper 21 being mounted in the passage 20 to control the proportion of hot gases going through the by-pass into the interior of member 19. Member 19 is 5 similar in construction to the member 14 with the exception of its generally triangular shape and the fact that it has side walls on both sides, one wall 22 being provided with one or more suitable apertures 23, three 10 being shown, to provide a communication between the passage formed by the contiguous member 14 and interior of the member 19. In the ordinary operation of the leer, the damper 21 will be opened to some extent, 15 allowing a controllable proportion of the hot gases from the fire box B to pass into the interior of the member 19 and thence through the openings or passage 23 into the flue passage formed by the contiguous member 14. 20 It may in some instances be sufficient, however, merely to provide enlarged apertures 23 through which gases may circulate back and forth between the interior of member 19 and the passage formed by the contiguous 25 member 14, due to eddy currents or otherwise, and without the use of by-pass such as is shown at 20.

The flue forming member 4, 4', 14 and 19 are surrounded throughout the greater part 30 of the length of the tunnel by insulating material 24 such as kieselguhr, which may be enclosed in a protecting casing 25 of some suitable material such as sheet metal. This layer of insulation is preferably thicker at 35 the hotter or entrance end of the tunnel and tapers either gradually or in steps toward the cooler end, whereby to control the rate of cooling of the gases within the flue C by limiting the loss of heat from the gases 40 therein to the surroundings, this manner of controlling the temperatures of the gases being desirable in some instances rather than the use of a part or all of the mechanism and method of operation hereinafter to be 45 described.

A source of hot gases, such as a fire box B, is connected to the flue C, this fire box including a combustion chamber 26 (Fig. 7) having an opening 27 in its side wall into 50 which is directed the flame from a suitable burner 28 for fluid or gaseous fuel. Inasmuch as the details of the internal construction of the fire box and of the burner form no part of my present invention, no further 55 description of this subject matter will be given. I have provided, however, for admitting diluting gases or air through the port 26a in the side of the fire box C, which gases or air may be forced into the opening 60 by the action of a controllable jet 26b in order that the resultant temperature of the gaseous media passing from the fire box into the flue C shall be substantially that at which it is desired to hold the glass for the release 65 of permanent strains.

Means may be provided for controlling the temperatures along the flue, such means including a plurality of dampered air inlet openings 28 communicating at spaced intervals with the flue C and serving to admit into the flue regulable amounts of atmospheric air to dilute and cool the gases therein and thus to control the temperature gradient in the tunnel. A longitudinally extending air conduit 29 is provided above the 70 cooler part of the leer communicating at its exit end with the draft producing device D and communicating at a plurality of spaced points along its length through dampered 75 passages 30 with the flue C. Thus it will be seen that by proper regulation of the dampers in the passages 30, the distance which the hot gases travel along the flue C 80 may be limited, as also may the distance which the cooling air travels in the reverse 85 direction from the cooler end 31 of the flue. In this way also the point of reversal of flow of gases in the flue C may be controlled at will.

The glass is moved through the leer upon 90 an endless reticulated wire mesh belt F, which rests directly upon the upper horizontal walls 6 of the members 4 and thus is in 95 good heat conducting relation therewith, this belt being driven by the means G and tensioned by suitable means shown diagrammatically at 32 (Fig. 1) as in the patent to Mulholland above referred to, the return strand 33 of the belt being supported on spaced rollers 34. The belt is substantially 100 as wide as the widest transverse dimension of the tunnel.

Thus it will be seen that I have provided a leer in which all four walls of the leer are 105 maintained at substantially an even temperature throughout any selected cross section of the leer, whereby the device may be used to anneal not only ordinary glassware, but also sheets of glass substantially as wide as the 110 leer. A fire box is located outside the vertical confines of the leer, so as to be easy of access and so as to prevent the conduction of substantial amounts of heat from the fire box 115 directly to the leer tunnel to cause "hot spots" therein and in general interfere with the accurate control of the temperature gradient. I have provided means for heating the triangular portion adjacent to the entrance end of the leer, which would otherwise be a dead spot. By constructing the flues of a plurality 120 of relatively similar parts, I have designed a leer, which is easy and cheap to make, and which uses less floor space in a factory than a leer in which the flues are in the form of a true helix, thus also practically eliminating 125 dead air spaces in and about the tunnel.

While I have shown and described but one embodiment of my invention, it is obvious 130 that many modifications might be made therein and many of the individual features might

be used in other combinations without departing from the spirit of the invention as set forth in the appended claims, which are to be construed as broadly as the state of the prior art permits.

5. I claim:

1. A glass annealing leer comprising an elongate tunnel having an entrance portion formed at right angles to the direction of movement of glass entering the tunnel, a substantially helical flue coiled about at least the ware-entering portion of said tunnel, means to pass hot gases through said flue to control the temperature within said tunnel, said flue having at least a portion of its first turn spaced from the entrance end of said tunnel due to the substantially helical construction thereof to form a substantially triangular space between such portion and the right angular entrance end of said tunnel, and means for supplying heat to said space.

2. A glass annealing leer comprising an elongate tunnel built up of a plurality of sectional parts, means for moving glass therethrough, a substantially helical flue associated therewith, each turn having at least a portion at an acute angle with the direction of movement of glass through said tunnel, means to supply hot gases to said flue, the leer having its entrance end formed at right angles with said direction, and means for supplying heat to the substantially triangular portion between the acute angle portion of the foremost turn of said flue and the right angular entering end of the leer, including by-pass connections to divert a part of said hot gases to and through said triangular portion.

3. A glass annealing leer comprising an elongate tunnel built up of a plurality of sectional parts, which when assembled form a substantially helical flue, means for moving glass through said tunnel, each turn of said flue having a portion extending across at least one wall of said tunnel at an acute angle with the direction of movement of glass therethrough, the leer having its entering end at right angles with said direction, and means for supplying heat to the space between the inclined portion of the first turn of said flue and the right angular entering end of the leer, whereby to maintain a substantially uniform temperature laterally of the leer at the entrance end thereof.

4. A glass annealing leer comprising an elongate tunnel built up of a plurality of interchangeable sectional parts, means for moving glass therethrough, a substantially helical flue associated with said tunnel, each turn of said flue having a portion extending across the roof of said tunnel at an acute angle with the direction of movement of glass therethrough, means to supply hot gases to said flue, the leer having its entering end formed at right angles with said direction,

and means for supplying heat to the space between the portion of the foremost turn of said flue extending across the roof of the tunnel and the right angular entering end of the leer, including a plurality of passages 70 through which said hot gases may circulate between said triangular portion and said foremost turn of said flue.

5. A glass annealing leer comprising an elongate tunnel built up of a plurality of interchangeable sectional parts, means for moving glass therethrough, a substantially helical flue associated therewith, each turn having a portion extending across the roof of said tunnel at an acute angle with the direction of movement of glass therethrough, means to supply hot gases to said flue, the leer having its entering end formed at right angles with said direction, and means for supplying heat to the substantially triangular portion between the portion of the foremost turn of said flue which extends across the roof of said tunnel and the right angular entering end of the leer, including a dampered by-pass connection for diverting 90 a portion of said hot gases into said triangular portion, and a passage through which the gases so diverted may pass into said foremost turn of said flue.

6. A glass annealing leer comprising an elongate tunnel, a substantially helical flue associated therewith, a fire box for supplying heated gases to said flue for controlling the temperatures in said tunnel, said fire box being located outside the vertical confines of the leer, and means to admit air to said fire box to dilute and cool the products of combustion therein and thereby to control the temperature gradient in said tunnel.

7. A glass annealing leer comprising an elongate tunnel, a substantially helical flue surrounding said tunnel, a fire box for supplying heated gases to said flue, said fire box being located outside the vertical confines of the tunnel and the flue, means to admit air to said fire box to dilute and cool the products of combustion therein to a temperature substantially the same as that at which it is desired to hold the glass for the release of permanent strains, means disposed at spaced intervals along the latter portion of said flue for withdrawing gases therefrom in controllable amounts, and means to limit the rate of temperature drop in the other portions of said flue by retarding the loss of heat therefrom to the surroundings, whereby accurately to control the temperature gradient in said tunnel.

8. A glass annealing leer comprising an elongate tunnel built up of a plurality of flue-forming members together forming passages extending at right angles to the longitudinal dimension of said tunnel, and a plurality of other flue forming members together forming diagonal passages connect-

ing the ends of the first named passages to form a substantially helical flue surrounding said tunnel.

9. A glass annealing leer comprising an elongate tunnel built up of a plurality of interchangeable flue-forming members together forming a plurality of similar passages extending at right angles to the direction of movement of glass through that portion of the tunnel opposite the respective members, and a plurality of other interchangeable flue-forming members together forming diagonal flues respectively connecting the opposite ends of contiguous pairs of the first named passages.

10. A glass annealing leer comprising an elongate tunnel, means for moving glass therethrough, a substantially helical flue having contiguous passes surrounding said tunnel, the portions of said flue at the bottom and sides of said tunnel extending perpendicular to the direction of motion of the glass therethrough and the top portions of said flue extending at an oblique angle to said direction to connect contiguous sections of the side and bottom portions thereof.

11. A sheet glass annealing leer comprising an elongate tunnel of relatively wide flat cross section, an endless reticulated conveyor belt substantially the same width as said tunnel for moving the glass therethrough, and a substantially helical flue entirely surrounding said tunnel from end to end thereof, the upper wall of the lower portion of said flue forming said floor of the tunnel.

12. A glass annealing leer comprising an elongate tunnel, an endless belt conveyor of open wire mesh material substantially as wide as the widest transverse dimension of the tunnel for conveying glass therethrough, a substantially helical flue of good heat conducting material, portions of the walls of which form the entire wall of said tunnel, and means for passing temperature controlling media through said flue accurately to control the temperatures of the glass on said conveyor in its passage through said tunnel.

13. In a glass annealing leer, a tunnel comprising a substantially helical flue formed at least in part by three sided flue forming members laid with their open sides in the same direction and forming with contiguous members substantially transversely extending passages, the sides of said members opposite their open sides forming the fourth sides of flue passages bounded on their other three sides by the three sides of the contiguous members.

14. In a glass annealing leer, a tunnel formed by a contiguous uninterrupted substantially helical flue built up of interchangeable flue forming parts, each of which forms not more than a single turn, in which contiguous turns of said flue are separated by a single flue wall thickness only.

15. A sheet glass annealing leer comprising

an elongate tunnel of relatively wide flat cross section, an endless reticulated conveyor belt for moving sheet glass therethrough, said belt being supported directly on the floor of said tunnel, a substantially helical flue entirely surrounding said tunnel from end to end thereof, a fire box disposed outside the vertical confines of said leer and communicating with said flue adjacent to the entrance end of said tunnel to supply hot gases thereto, dampered air inlet ducts disposed at intervals along the hotter portions of said flue for admitting controllable amounts of atmospheric air to dilute and cool said hot gases, said flue being open to the atmosphere adjacent to the discharge end of the leer, a draft impelling device, and a plurality of dampered connections between said draft impelling device and the cooler portions of said flue for withdrawing the media therefrom, the portions of said flue at the bottom and sides of said tunnel extending substantially perpendicular to the direction of movement of the glass therethrough and the top portions of said flue extending at an oblique angle to said direction, whereby to maintain the glass in any transverse section of said tunnel substantially at a uniform temperature.

Signed at Hartford, Connecticut, this 6th day of January, 1930.

KARL E. PEILLER.
